UNITED STATES PATENT OFFICE.

BERNARD S. McFARLAN, OF SPOKANE, WASHINGTON.

ADVERTISING-SIGN.

1,102,160.

Specification of Letters Patent. Patented June 30, 1914.

Application filed August 14, 1912, Serial No. 715,096. Renewed May 21, 1914. Serial No. 840,121.

To all whom it may concern:

Be it known that I, BERNARD S. McFARLAN, a citizen of the United States, residing at Spokane, in the county of Spokane and 5 State of Washington, have invented certain new and useful Improvements in Advertising-Signs, of which the following is a specification.

This invention relates to improvements in 10 exhibiting apparatus, and particularly to such as provide for color changing effects.

The object in view is the projecting of a great variety of colors and shades in succession by a cheap and simple apparatus.

15 With these and further objects in view, as will in part hereinafter be set forth and in part become apparent, the invention comprises certain novel construction, combination and arrangement of parts as herein 20 specified and claimed.

In the accompanying drawings. Figure 1 is a perspective view of an apparatus embodying the features of the present invention; Fig. 2 is a longitudinal, vertical central section therethrough; Fig. 3 is a transverse horizontal section therethrough taken on a plane indicated by line 3-3 of Fig. 2. Fig. 4 is a fragmentary perspective view showing more clearly certain details of the 25 general structure of the device. Fig. 5 is a horizontal sectional view of the revolving cylinder.

Referring to the drawings by numerals, 30 1 indicates a housing or casing having an open front, preferably surrounded by a frame 2 adapted to receive a sign bearing slide 3. The frame 2 is preferably formed with a slot 4 at one end with grooves along its upper and lower sides for receiving and 35 guiding the sign bearing slide 3. The slide 3 may consist of transparent glass on which the sign to be displayed has been painted or otherwise applied, or may consist of any transparent plate or screen similarly bearing a sign, or in lieu thereof a sheet of translucent paper bearing the sign may be employed.

Substantially centrally of the housing 1 is arranged a lamp 5 which may be of any 40 convenient type, but preferably, where possible, consists of an incandescent electric bulb sustained on a spider, or other open-work support 6, mounted on the floor of the housing 1, said flooring being apertured centrally for the free admission of air through

the bottom of the housing and up past the lamp.

For convenience of reference the open side of the housing 1 will be referred to as the front and the opposite side as the rear. 60 In the rear of the lamp 5 is arranged a suitable reflector 7, and at the front are arranged translucent colored screens 8, 9 and 10, each occupying its relative amount of space in front of the lamp, such space being 65 preferably equally divided, but obviously capable of other divisions. The screens 8, 9 and 10 also are preferably flat and disposed in angular relation, but may be otherwise shaped. Though each of the said 70 screens is translucent it is preferably colored, and for purposes of illustration it may be assumed that the primary colors are employed, for instance the screen 8 being colored blue, the screen 9, yellow, and the 75 screen 10 red. Obviously other colors or shades may be employed with varying effects, according to the results desired.

The reflector 7, and screens 8, 9 and 10 are supported by and held stationary upon 80 the floor of the casing 1 and are surrounded by a revolving cylinder 11. The cylinder 11 is made up of a series of screens 12, 13, and 14 spaced apart by alternating screens 15. All of the screens 15 are preferably merely 85 clear, while the several screens 12, 13, and 14 are colored, as for instance screen 12 may be colored red, screen 13 blue and screen 14 yellow. The primary colors are here referred to by way of example as they afford 90 almost a limitless variety of shades from the method of commingling colors as herein-after set forth, but it is apparent that other colors than red, blue and yellow may be utilized on screens 12, 13, and 14. In fact 95 different colors may be utilized on said screens from the colors employed on screens 8, 9 and 10, but by preference I am employing colors on screens 8, 9 and 10 bearing a fixed value in relation to the colors of screens 100 12, 13 and 14.

Within the cylinder 11 is arranged a supporting bracket 16, preferably mounted on the floor of the housing 1 and extending to a point adjacent to the outer end of the cylinder 11. The bracket 16 is preferably formed of spring material and has its end portion terminating in a horizontal section which is slit as at 17, through which extends vertically, a bearing pin 18. The bracket may 110

be apertured at 19 for more readily admitting the pin 18, but the pin is of sufficient size when projected through the aperture to slightly spread the slit 17 and thus cause the parts of the bracket to clamp against the sides of the pin and firmly hold the pin in place. The pin may be readily released by inserting an instrument in the slit 17 and spreading the same open. Mounted on the pin 18 is a bearing sleeve 27 which is formed with an upwardly tapering conical recess into which the pin 18 extends, thus forming a stepped bearing, the upper end of the sleeve being closed and terminating in a threaded portion 20.

A power-wheel 21 is arranged with its central portion resting upon and clamped to a shoulder at the upper end portion of the sleeve 27, the wheel being retained in position by a nut threaded onto the threaded portion 20 above the clamped portion. Each of the several blades of the wheel is preferably formed at its outer end with a tab or projection 22, which extends through a ring 23 surrounding the wheel, each of said tabs being bent or swaged over to permanently support the ring on the wheel and to maintain the parts of the wheel in their given positions. The cylinder 11 has its upper end surrounding and snugly inclosing the ring 23 and fixed thereto by detachable bolts, or otherwise, as preferred.

Immediately above the cylinder 11, the housing 1 is preferably formed with a hollow hood 25, upstanding from the housing a distance sufficient to provide ventilating apertures 26 in vertical portions of the hood, whereby air is permitted to escape freely from the housing, while the interior parts are protected against the weather.

In operation, the heat of the lamp 5 causes an upward current of air which, traveling past the wheel and out of the apertures 26, serves to revolve the wheel and thus revolves the cylinder 11. Assuming that the screen 13 is directly in front of screen 9 when the light is turned on, a yellow light is projected through the screen 9 and will appear through the blue screen 13 as a green light, while the edges of the transparent screen 15 near screen 13 will show a yellow light and the other portions of the said screen 15 will show varying shades relative to the proportionate amount of blending, blue from screen 8 with the yellow from screen 9, and red from screen 10 with the yellow of screen 9. The transparent screen 15 when directly opposite screen 8 will, of course, show blue and when directly opposite screen 10 will show red. As a further illustration of the great variety of shades and colors projected by the present improved apparatus it will be observed that, as the blue from screen 13 reaches the point in front of the red screen 10, a purple light

will be projected, various shades having appeared between the point where the screen 13 showed green to the point where it shows purple. As the blue screen 13 is passing to one side of the yellow screen 9, the yellow light will be projected as a yellow light through the central portion of the screen 15, and then the red screen 12 will next appear in front of the yellow screen 9 with the resultant projection of an orange light.

When the slide 3 bearing the sign assumes the form of the glass plate the same is preferably in the form of prism glass in order to afford the advantages of diffusion incident to a prism.

It will be particularly noted that the structure and operation set forth are such that the successive blending of the primary colors will present the appearance on the face of the sign screen of successive undulations of light of varying colors, shades and tints.

What I claim is:

1. The combination of a translucent sign, light projecting means disposed for projecting rays of light through the sign, a translucent screen disposed in the path of the light rays from said light projecting means and arranged with three flat faces disposed in angular relation to each other, each of the flat faces bearing one of the primary colors different from the other two, a translucent cylinder surrounding the screen and the light projecting means and divided into sections alternating, clear, and colored, and the colored sections being provided each with one of the primary colors and the several colored sections being arranged in succession with respect to their colors, and means for revolving the cylinder.

2. The combination, with light projecting means, of a translucent screen bearing a plurality of colors disposed in the path of rays from the light projecting means, a reflector at the opposite side of the light projecting means, a translucent cylinder surrounding the light projecting means and screen and bearing different colors, a bracket extending longitudinally of and within the cylinder in the rear of the reflector and having an upstanding pin at its upper end, and a power wheel journaled on said pin and connected with the cylinder for rotating the cylinder when the wheel is moved by movement of air with respect to the light projecting means.

3. The combination, with a sign support adapted to sustain a translucent sign, and a light projecting means adapted to project rays of light through such a sign, of a plurality of translucent differently colored screens arranged between the light projecting means and the sign, a cylinder, surrounding the said light projecting means and screens, comprising a series of translu-

cent screens spaced apart, and transparent screens alternating therewith, and means for revolving said cylinder.

4. The combination with light projecting means, of a plurality of translucent, differently colored screens disposed in the path of rays of light from said light projecting means, a series of translucent screens spaced apart and disposed to be moved across the

path of said light rays, and transparent 10 screens alternating with the last mentioned translucent screens.

In testimony whereof I affix my signature in presence of two witnesses.

BERNARD S. McFARLAN.
